Attorney

UNITED STATES PATENT OFFICE

OSCAR L. JOHNSON, OF SISTER BAY, WISCONSIN

RAZOR-BLADE-STROPPING HOLDER

Application filed September 20, 1928. Serial No. 307,800.

The present invention relates to improvements in safety razor blade holders and has for its principal object to provide a device for holding a safety razor blade during the 5 sharpening of the cutting edges thereof.

An important object of the present invention is to provide a safety razor blade stropping holder which includes a pair of coacting hingedly connected clamping plates 10 between which a safety razor blade is adapted to be secured against slidable movement, means being provided for securing the clamping plates together, additional means being provided for automatically swinging 15 the top clamping plate upwardly when the locking means is released to facilitate the removal of the blade from the holder.

Still a further object is to provide a safety razor blade stropping holder of the above 20 mentioned character which is simple in construction, inexpensive, strong and durable and further well adapted to the purposes for which it is designed.

Other objects and advantages will become 25 apparent during the course of the following description.

In the accompanying drawing, forming a 30 part of this specification, and in which like numerals indicate like parts throughout the same:

Figure 1 is a top plan view of the safety razor blade stropping holder embodying my 35 invention, showing the clamping plate in closed position, and holding the safety razor blades therebetween,

Figure 2 is a similar view showing the top clamping plate swung to a horizontal position away from the bottom clamping plate,

Figure 3 is a longitudinal sectional view 40 through the holder and

Figure 4 is a transverse section taken approximately on the line 4—4 of Figure 1.

In the drawing wherein for the purpose of illustration is shown the preferred embodiment of my invention, the numeral 1 designates generally my improved safety razor blade stropping holder, the same comprising a hollow elongated handle 2, the upper forward end portion thereof being cut 45 away.

A flat elongated strip 3 is arranged within the handle 2 and formed on the forward end of this strip is the rigid bottom clamping plate 4, the same being disposed across the cutaway forward end portion of the hollow 55 handle 2.

The strip 3 may be secured within the hollow handle 2 in any suitable manner. Above the strip 3 and extending transversely across said strip, are spaced guide straps 5, 60 the purpose of which will be presently described.

The clamping plate 4 may be soldered to the upper edge of the cutaway portion of the hollow handle and adapted for cooperation with the bottom clamping plate 4 is a similar shaped top clamping plate 6, said clamping plates being hingedly connected together along their rear edges as at 7.

An arcuate shaped packing plate 8 is 70 soldered to the outer face of the top clamping plate 6 so that when the clamping plate 6 is disposed on top of the clamping plate 4, the arcuate portion 8 will form an extension of the hollow handle 2 as obvious from the construction disclosed in Figures 1 and 3.

Extending upwardly from the bottom clamping plate 4 adjacent the forward longitudinal edge thereof are the spaced pins 9 that are adapted to pass through the usual 80 opening provided in certain types of safety razor blades and the adjacent end portion of the top clamping plate is formed with openings 10 to accommodate the pins 9 when the top clamping plate is disposed in superposed relation with respect to the bottom clamping plate as will be presently described.

The clamping plates are of such width as to be less than the width of the razor blade whereupon the cutting edge of the razor blade will protrude beyond the free longitudinal edges of the coacting clamping plates in the manner as shown in Figures 1 and 4.

My invention further includes the provision of means for positively securing the clamping plates in a closed position and to this end, a locking bar 11 extends longitudinally through the hollow handle 2 and is arranged for slidable movement between the 95

top face of the strip 3 and the guides 5 as suggested in Figure 3.

The locking bar is in the form of a narrow strip of metal and is of a length greater than 5 that of the hollow handle. The outer end of the lock bar is bent to form a hook 12 for detachable engagement over the outer ends of the clamping plates 4 and 6 and the locking bar is further formed at a point inwardly of the hooked outer end 12 with a struck out hook 13 that is operable within registering openings 14 and 15 formed in the inner end portion of the clamping plates 4 and 6.

15 The hook 13 is adapted to engage with the inner end portions of the clamping plate. A head or knob 16 is carried by the inner ends of the locking bar 11 for disposition outwardly of the inner end of the handle 2 whereby to actuate said lock bar.

20 An expandable coil spring 17 is connected at one end to the intermediate portion of the locking bar, the other end being secured to one of the transverse straps 5 as shown very 25 clearly in the dotted lines in Figure 2.

This spring 17 normally urges the locking bar 11 inwardly toward the free end portion of the handle 2.

When the knob or head 16 is pushed inwardly against the tension of the coil spring 17, the hooks 12 and 13 are disposed in an 30 inoperative position. The razor blade A that is to be sharpened is then positioned on the bottom plate 4 after which the top clamping 35 plate 6 is swung over on top of the blade with the pins 9 protruding through the opening 10.

By releasing the knob 16, the coil spring 40 17 will automatically move the locking bar 11 inwardly so that the hook 12 will engage over the outer ends of the bolt clamping plate while the hook 13 will engage both 45 of the inner end portions of said clamping plate to positively secure the clamping plates in such relation as to insure against the razor 50 blade A being disengaged from the holder during the use of the same in stropping or sharpening the blade.

After the blade has been sharpened, the 55 same can be readily and easily removed from the holder by pushing forwardly on the knob 16 so as to disengage the hooks 12 and 13 from cooperative engagement with the clamping plate and a spring pressed plunger 59 18 that is carried by the bottom portion of the forward end of the handle 2 and which is operable through an opening provided in the rear edge portion of the base plate 4 will exert an upward pressure on the hinged top 64 plate 6 to move the same upwardly and away from the bottom clamping plate so that said top clamping plate can be easily swung to an open position and the blade removed.

It is of course understood that the spring 65 pressed plunger 18 is held under tension

when the clamping plates are secured together.

It will thus be seen from the foregoing description, that I have provided a safety razor blade stropping holder that will be at all times efficient and reliable in carrying out the purposes for which it is designed and due to its simplicity, the same can be readily and easily operated. Also a device of this character can be constructed at a very low cost and the same will be strong and durable.

70 While I have shown the preferred embodiment of my invention, it is to be understood that various changes in the size, shape and arrangement of parts may be resorted to without departing from the spirit of the invention and the scope of the appended claims.

75 Having thus described my invention, what I claim as new is:

1. A safety razor blade stropping holder comprising a hollow handle, a bottom blade clamping plate carried by the forward end of the handle, a coacting top clamping plate hingedly connected along one of its longitudinal edges to the adjacent longitudinal edge of the bottom clamping plate, and means for securing the clamping plates together to hold a safety razor blade therebetween, said means comprising a slideable locking bar extending through the handle and below the bottom clamping plate, the forward end of said clamping bar being bent to form a hook for engagement over the outer ends of the clamping plate, a hook struck out from the intermediate portion of the locking bar, the inner end portions of the clamping plate being formed with communicating openings through which the last mentioned hook is operable, said last mentioned hook adapted to engage the recessed inner end of the clamping plates, an actuating knob on the rear end of the locking bar, and spring means associated with the locking bar for normally holding the same in a rearwardly urged position to maintain the hook in locking engagement with the clamping plate.

100 2. A safety razor blade stropping holder comprising a hollow handle, a bottom blade clamping plate carried by the forward end of the handle, a coacting top clamping plate hingedly connected along one of its longitudinal edges to the adjacent longitudinal edge of the bottom clamping plate, and means for securing the clamping plates together to hold a safety razor blade therebetween, said means comprising a slideable locking bar extending through the handle and below the bottom clamping plate, the forward end of said clamping bar being bent to form a hook for engagement over the outer ends of the clamping plate, a hook struck out from the intermediate portion of the locking bar, the inner end portions of the clamping plate being formed with communicating openings through which the last mentioned hook is operable, said last mentioned hook adapted to engage the recessed inner end of the clamping plates, an actuating knob on the rear end of the locking bar, and spring means associated with the locking bar for normally holding the same in a rearwardly urged position to maintain the hook in locking engagement with the clamping plate.

the clamping plate being formed with communicating openings through which the last mentioned hook is operable, said last mentioned hook adapted to engage the recessed inner end of the clamping plates, an actuating knob on the rear end of the locking bar, and spring means associated with the locking bar for normally holding the same in a rearwardly urged position to maintain the hook in locking engagement with the clamping plate, and means for automatically swinging the top clamping plate upwardly when the locking means is released.

3. A razor blade holder comprising a hollow tubular handle having its upper forward end portion cut away to provide a lower semi-circular extension, a pair of clamping plates having co-acting means for gripping a razor blade therebetween, one of said plates being fixed to and bridging the said semi-circular extension and the other plate having an arcuate shaped backing plate adapted, when the clamping plates are in raised clamped position to form a continuation of the upper end of the said handle, means for securing the clamping plates together, and means for automatically raising the hinged top clamping plate upwardly when said locking means is released, the last mentioned means comprising a spring pressed plunger carried by the extension of the handle and through an opening provided adjacent the hinged edge of the bottom clamping plate for engagement with the adjacent portion of the top clamping plate.

4. A razor blade holder comprising a hollow tubular handle having the upper forward end portion cut away to provide a lower semi-circular extension, a pair of clamping plates having co-acting means for gripping a razor blade therebetween, one of said plates being fixed to and bridging the said semi-circular extension and the other plate having an arcuate shaped backing plate adapted when the said clamping plates are in blade clamping position for forming a continuation of the upper end of said handle, the said extension-supported plates having an elongated integral portion projecting within the said hollow handle and provided with guiding means, a slidably spring pressed locking bar operable in the said guiding means of the said extension supported plate, and having hooks operable within registering openings in the said clamping plate for locking the latter together, and means for automatically opening the said plate when said locking means is released.

In testimony whereof I affix my signature.

OSCAR L. JOHNSON.
